UNITED STATES PATENT OFFICE.

ANTON BECKER, OF COLUMBUS, OHIO, ASSIGNOR TO THE RALSTON STEEL CAR COMPANY, OF COLUMBUS, OHIO.

TANK-CAR.

1,237,156.

Specification of Letters Patent. Patented Aug. 14, 1917.

Application filed March 14, 1917. Serial No. 154,763.

To all whom it may concern:

Be it known that I, ANTON BECKER, a citizen of the United States, and a resident of Columbus, in the county of Franklin and State of Ohio, have invented certain new and useful Improvements in Tank-Cars; and I do hereby declare the following to be a full, clear, and exact description of the invention, such as will enable others skilled in the art to which it appertains to make and use the same.

This invention relates to improvements in tanks cars and more particularly to improved anchoring means for connecting the tank with the underframe, one object of the invention being to provide a simple and efficient anchor or saddle which may be readily made from a single piece of metal and secured to the center girder members in a manner to effectually support the tank thereon and guard against the shearing action on the bolts which secure the anchor or saddle to the webs of said center girder members.

With this and other objects in view, the invention consists in certain novel features of construction as hereinafter set forth and pointed out in the claims.

In the accompanying drawings; Figure 1 is a fragmentary transverse sectional view illustrating the application of my improvements; Fig. 2 is a plan view of the anchor or saddle, and Fig. 3 is a view showing the same in side elevation.

1, 1 represent the members of a center girder of the box type and may consist of channel beams.

In constructing my improved anchor or saddle 1, I may provide a plate having a central longitudinal slot and transverse slots at respective ends of the central slot, similar to the construction shown in my previous patent issued August 31, 1915 and designated No. 1,151,851.

The saddle 1 will be curved to conform to the contour of the tank 2,—suitable rivets 3 being employed to secure it to the latter. The slotting of the plate as above described provides tongues 4 which are bent downwardly so as to be disposed between the center girder members and against the inner faces thereof, to which said tongues are secured by means of bolts or rivets passing through the holes 5.

The ends of the anchor or saddle 1 are bent downwardly and then outwardly to form transverse flanges 6 which rest upon the cover plates 7 spanning the center girder members. The depressed flanges 6 will preferably be perforated as at 8 for the passage of bolts or rivets which secure the same to said cover plates and to the upper flanges of the center girder members.

By the provision of the depressed flanges 6, means are afforded for mounting the anchor or saddle upon the center girder in a manner to prevent shearing of the bolts or rivets which secure the depending tongues 4 to the webs of the center girder members.

Having fully described my invention what I claim as new and desire to secure by Letters-Patent, is:

1. A tank car anchor comprising a plate provided with depending tongues adapted to be secured to the web portion of a center girder, and having depressed portions at its ends to rest upon the center girder.

2. In a tank car structure, the combination with a tank and a center girder comprising parallel members, of an anchor secured to the tank and having depending tongues secured to the web portions of the center girder members.

3. In a tank car structure, the combination with a tank and a center girder comprising parallel members, of an anchor secured to the tank and having tongues depending between the center girder members and secured to the inner faces thereof.

4. In a tank car structure, the combination with a tank and a center girder comprising parallel members, of an anchor secured to the tank and having depending tongues secured to the web portions of the center girder members, said anchor having depressed portions at its ends supported upon the top of the center girder.

In testimony whereof, I have signed this specification in the presence of two subscribing witnesses.

ANTON BECKER.
